Primary Examiner — Rosemary K Tarcza(74) *Attorney, Agent, or Firm* — K&L Gates LLP(57) **CLAIM**

The ornamental design for a sink attachment device, as shown and described herein.

DESCRIPTION

FIG. 1 is a perspective view of a sink attachment device. FIG. 2 is a perspective view of a sink attachment device. FIG. 3 is a perspective view of a sink attachment device. FIG. 4 is a perspective view of a sink attachment device. FIG. 5 is a perspective view of a sink attachment device. FIG. 6 is a perspective view of a sink attachment device; and, FIG. 7 is a perspective view of a sink attachment device. The broken lines shown in the drawings are included for the purpose of illustrating environmental structure and form no part of the claimed design.
